UNITED STATES PATENT OFFICE

2,466,126

SPRINKLER STOPPER

Samuel Siegel, Lynchburg, Va., assignor of one-half to Benjamin Schewel and Bertram R. Schewel, Lynchburg, Va.

Application April 8, 1946, Serial No. 660,522

8 Claims. (Cl. 169—1)

1

This invention relates to emergency stoppers for sprinkler heads in fire extinguishing spray systems of the overhead pipe line type sometimes become opened by other causes than by heat from fire. Naturally when this happens considerable damage from the water spraying forth results. Therefore, it is important to provide some emergency arrangement for plugging the water outlet of a prematurely or accidentally opened sprinkler head until another fusible connection can be installed to hold the valve in the head closed. Accordingly, one of the objects of the invention is to provide a novel readily applied emergency stopper for tightly sealing such prematurely opened sprinkler heads.

Another object is to provide a novel device for inserting a novel emergency stopper in the overhead sprinkler head to seal off the escaping water. A further object is to provide, as an article of manufacture, an emergency stopper of light weight and durable material adapted to last indefinitely for continued use as a stopper until the emergency condition has been corrected.

Other objects and advantages of the invention will appear from the following detailed description when read with reference to the accompanying drawings, wherein:

Figure 1 is a perspective view of the novel emergency stopper.

Figure 2 is a longitudinal cross section view of the stopper.

Figure 3 is a view of the same in top plan elevation.

Figure 4 shows plan and side views of a novel fluid sealing gasket used in the stopper structure.

Figure 5 shows a side elevation of the novel stopper supported by a novel bracket device used for inserting the stopper through the yoke of a sprinkler head; and

Figure 6 is an end view looking from the tapered end of the stopper back through the yoke as it appears when inserted in the yoke by the attaching bracket.

Referring to the drawings and first with particular reference to Figures 1, 2, and 3, there is shown the novel emergency fluid sealing wedge assembled and ready to be applied to a sprinkler head. The body of the wedge comprises a rectangular frame 10 of light weight material such as aluminum having sloping side walls 11 and 12, and end walls 13 and 14.

The end wall 13 is relatively higher than the end wall 14 and thus the side walls slope downwardly from the top of end walls 13 to the top of wall 14 to give the appearance of a wedge.

The side walls 11 and 12 have inwardly extending flanges 15 and 16, respectively, with enlarged portions 19 adjacent the shorter end wall 14. These flanges have a narrow elongated slot

2

between their top as shown in Figures 2 and 3 and a rectangular opening of much greater width between the side walls at the bottom for the purpose to be hereinafter explained.

5 The enlarged portions 19 of the flanges have aligned openings therein and through these openings extends a hinge pin 20. Pivoted on the hinge pin 20 is a stopper 21. The stopper 21 is triangular in shape so that its top edge 22 slopes in the same direction with the top edges of the sloping side walls 13 and 14 for the entire length of the slot between the flanges 15 and 16 of the side walls. This edge 22 may be provided with a longitudinal groove, which groove serves to cooperate with the inner end of a stud A, which holds the spray baffle on the usual sprinkler head yoke B. A portion of the bottom edge of the stopper 21 is formed with a flat head 23, which is of the general appearance of a hammer head. As the stopper 21 is shorter than the rectangular space defined by the walls of the frame 10, it has free pivotal movement on the hinge pin 20.

Secured to the underside of the frame 10 by bolts or screws 24 and 25 threaded into threaded openings in the bottom edge of each end wall 13 and 14, respectively, is an aluminum plate 26 with a rectangular opening. Clamped between this plate 26 and the bottom edges of the frame 10 is soft rubber plate or gasket 27.

30 This rubber plate 27 is preferably molded, so as to provide a relatively thicker centrally positioned pad 28, which substantially equals the thickness of the metal clamp plate 26 and is of a length and breadth such as to fit and fill in the rectangular opening in the plate 26. Thus the flat head portion 23 of the freely pivoted stopper 21 rests upon the soft rubber pad 28, which pad, due to its thickness normally holds the top sloping edge 22 of the stopper 21 in slightly elevated position 35 above the sloping top edges of the side walls 11 and 12. Accordingly, if the fusible metal of a sprinkler head 30 gives way accidentally, then the frame 10 with the slightly elevated stopper 21 may be slid into the yoke B of a sprinkler head 30 so the inner end of stud 31 projects into the groove along edge 22 of the stopper, as shown in Figure 5. This causes a wedging action between the end of the spray baffle stud A of the sprinkler head and the sloping groove in the top edge 22 of the stopper 21, whereby the flat head 23 is pressed down on the soft rubber pad portion 28 and seals it tightly over the water outlet 32 of the sprinkler head.

45 As shown in Figures 5 and 6, a novel bracket 35 may be used to insert the emergency stopper into the sprinkler head yoke B. To provide for use of the bracket 35 the end wall 13 contains a threaded opening 36, see Figures 3 and 5. Into this 50 opening a thumb screw 37 carried by the bracket 60

is threaded so as to attach the wall 13 to the bracket.

The bracket 35 is curved so as to be offset from and go around the usual overhead water pipes 38 and has a flattened end 39 with a threaded opening for the thumb screw 37. This flat end 39 seats flush against the end wall 13 when the thumb screw connects the bracket to the emergency stopper frame 10. The other end of the bracket contains a socket 40 adapted to receive a handle 41 of any desired length.

Thus, I have provided a novel emergency stopper for thermally actuated fire sprinkler systems, which is of light weight durable material, such as aluminum with a rubber sealing pad, which can be easily and quickly inserted into a yoke on a sprinkler head to seal an open water outlet therein. Also, I have provided a novel device adapted to facilitate the insertion of my novel emergency stopper through the usual sprinkler head yoke quickly and expeditiously.

Without further description it is thought that the above and other advantages of this invention will be apparent, and it is to be understood that although only one embodiment of the invention is illustrated, the same is readily capable of various other specifically different embodiments within its spirit and scope as defined in the appended claims.

I claim:

1. An emergency device for sprinkler heads with a yoke comprising a wedge-shaped body with an elongated opening extending through the same from top to bottom, a stopper pivoted in the body in the opening, a sealing plate having a rubber pad portion secured to the bottom of the body over the said opening, and means carried by said stopper adapted to engage and press the pad portion of said rubber plate down tightly over a water outlet when the said body is wedged into the sprinkler head yoke.

2. An emergency fluid sealing wedge for fire sprinkler heads comprising a rectangular frame having end walls of different heights and side walls sloping from one end wall to the other, a pivoted member between the said side walls, a flat head carried by said pivoted member and a rubber pad mounted on the frame below said pivoted member upon which said head is adapted to rest by gravity, said member having a top sloping edge projecting above the top edges of said side walls, whereby upon insertion in a sprinkler head said member is forced downward so that the said flat head presses the rubber pad down over the water outlet of the sprinkler head.

3. An emergency fluid sealing wedge for fire sprinkler heads comprising a rectangular frame having end walls of different heights and side walls sloping from one end wall to the other, a pivoted member between the said side walls, a flat head carried by said pivoted member, a rubber pad mounted on the frame below said pivoted member upon which said head is adapted to rest by gravity, said member having a top sloping edge projecting above the top edges of said side walls, whereby upon insertion in a sprinkler head yoke said member is forced downward so that the said flat head presses the rubber pad down over the water outlet of the sprinkler head, and an opening in the highest end wall of the wedge to provide for attachment of the wedge to a bracket for inserting the same into a sprinkler head yoke of an overhead sprinkler system.

4. In combination with heat operated spray heads for fire extinguisher systems wherein said heads include a yoke above the water outlet and a stud extending through the yoke at the top, an emergency stopper comprising a wedge-shaped triangular frame, a pivoted member in said frame having a top edge with a groove therein adapted to be engaged by said stud when the frame is inserted in the yoke, and a sealing gasket mounted across the bottom of the frame adapted to be pressed tightly over the water outlet by said pivoted member as the grooved top edge is moved along under the stud in the sprinkler head yoke.

5. An emergency closure device for sprinkler heads with a yoke, comprising, a wedge-shaped body with an elongated opening extending through the same from top to bottom, a stopper pivoted in the body in the opening, a sealing plate having a rubber pad portion secured to the bottom of the body over the said opening, and a head carried by said stopper adapted to engage and press the said pad portion of said sealing plate down tightly over a water outlet when the said body is wedged into a sprinkler head yoke.

6. An emergency closure device for sprinkler heads with a yoke, comprising, a wedge-shaped body formed with an elongated opening extending therethrough from top to bottom, a member pivoted to the body in said opening, and a sealing gasket mounted over the bottom of said opening adapted to be engaged by said member and pressed into fluid sealing connection over a sprinkler head outlet when said device is inserted in the sprinkler yoke.

7. An emergency closure device for sprinkler heads with a yoke, comprising, a wedge-shaped body formed with an elongated opening extending therethrough from top to bottom, a member pivoted to the body in said opening, a flat head formed from the bottom of said pivoted member, and a yieldable resilient member mounted over the bottom of said wedge-shaped body adapted to be pressed by the flat head of said pivoted member into fluid sealing contact over the outlet pipe of a sprinkler head when said member is wedged under the yoke of the said head.

8. An emergency closure device for sprinkler heads, including, a yoke above the water outlet and a stud for the spray baffle, comprising, a wedge shaped body having an elongated opening extending vertically therethrough from top to bottom, a stopper member pivoted to the body and having an upper portion exposed through the top of the opening and having a head on its bottom portion movable relative to the bottom of the opening, whereby, when the wedge shaped body is pushed into the yoke of the sprinkler head, the upper portion of the stopper member engages the said stud of the spray baffle, and pushes the stopper member downward in the opening so that its head moves toward the water outlet.
